UNITED STATES PATENT OFFICE

JOHN R. EMMERT, OF CHICAGO, ILLINOIS, ASSIGNOR TO EMIL J. PAIDAR CO., OF CHICAGO, ILLINOIS, A CORPORATION OF ILLINOIS

CHIROPODIST CHAIR

Application filed July 16, 1928. Serial No. 293,003.

This invention relates to a chiropodist chair and concerns itself with means for adjusting the foot rest and back to any desired angle.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is an elevational view of a chiropodist chair involving this invention;

15 Figure 2 is an enlarged front elevational view of the leg rest;

Figure 3 is an enlarged side elevational view taken upon the line III—III of Figure 2;

20 Figure 4 is an enlarged sectional view taken upon the line IV—IV of Figure 3;

Figure 5 is an enlarged sectional view taken upon the line V—V of Figure 2;

Figure 6 is an enlarged fragmentary side 25 elevation of the chair illustrating the means for adjusting the back;

Figure 7 is a rear elevational view of the structure shown in Figure 7;

Figure 8 is an enlarged sectional view taken 30 upon the line VIII—VIII of Figure 7; and

Figure 9 is an enlarged sectional view taken upon the line IX—IX of Figure 8.

As illustrative of this invention, there is shown a chair consisting of a pedestal 1 which 35 supports a seat rail 2 upon which a cushion 3 is supported. From the seat rail, there depends an apron 4 upon which a foot board or rest 5 is supported upon which the occupant is adapted to place his feet when sitting up-right.

A pair of rods or brackets 6 are adjustably secured to the foot board, preferably by slidably extending thru suitable bores therein. These rods have upwardly offset parts 45 6a upon which vertical bearings 7 are mounted. The bearings 7 are connected by a bridge 8 provided with a groove notch 9 (Figure 5) in which the end of a latch lever 10 is secured. The latch lever 10 is provided with 50 a circular aperture thru which a rod 11

passes, and a coil spring 12 surrounds the rod 11 between said lever and the lower surface of the bridge and tends to force the same downwardly to bind against the rod 11 to frictionally maintain the same in adjusted position. The rod 11, may be quickly released by pulling upward upon the lever 10, and then may be done by the knee of the operator without using his hands.

The aforementioned rod 11 supports a stirrup or U-shaped member 14, having guide rods 15 extending thru the bearings 7. A foot or leg rest 16 is pivotally supported upon the upwardly extending arms 14a of the stirrup. Upon one end of the foot rest, there is pivoted a link 17 which carries a bolt 18 extending thru a slot 19 in the adjacent leg of the stirrup. A nut 20 upon the bolt is adapted for adjustably securing the same in any part of the slot. By loosening the nut, the link 70 may be adjusted up or down to vary the inclination of the foot rest 16.

The back 21 of the chair is provided with a pair of hinge members 22 which are pivoted at their lower ends to upright arms 23 of U-shaped casting 24 upon the seat rail. This construction will allow the back to swing from an upright to an inclined position as shown in Figure 6.

Means are provided for maintaining the back at any suitable angle of inclination. This means consists of a rod 25 pivoted at its upper end to a casting 26 upon the back of the chair and extending thru an aperture in a locking plate 27 supported in a housing 28 attached to the rear of the seat rail 2. The locking plate 27 is provided with a pair of sockets 28 into which tenons on hand levers 29 extend. These hand levers 29 extend thru the casing 28 and are provided with upwardly extending handles 30. A coil spring 31 surrounds the rod 25 and is confined between the top of the casing 28 and locking plate. The casing 28 is provided with a suitable slot 32 thru which the rod 25 extends and in which it may swing. It will be obvious that the spring 31 will normally force the locking plate 27 into frictional engagement with the rod 25 to maintain the same in any predetermined position. When it is desired to ad-

just the back of the chair, the rod 25 is released by actuating one of the levers 29. This can be quickly done.

In the use of the chair the leg rest 16 may be adjusted thru the sliding brackets 6 to vary its distance from the chair and may be raised and lowered by merely pushing upward upon the lever 10, either by the hand or knee for unlocking the rod 11. This is an exceedingly quick and easy adjustment. The leg rest 16 may be properly tilted by the link 17. Likewise, the back 21 may be tilted to any desired angle by rotating or operating one of the levers 29 to release the bar 25. This is also a very quick and easy adjustment. It is therefore possible to adjust one to suit the other in order to secure the desired position for the patient or occupant of the chair.

I am aware that many changes may be made and numerous details of construction may be varied through a wide range without departing from the principles of this invention and I, therefore, do not propose limiting the patent granted hereon otherwise than necessitated by the prior art.

I claim as my invention:

In a chiropodist chair having a foot board, a bracket comprising a bearing having a pair of rods slidably mounted in said foot board, said bearing having spaced apertures and an intermediate aperture, a foot rest having spaced rods extending through said spaced apertures and an intermediate rod extending through said intermediate aperture, said intermediate aperture having an enlarged portion, a spring mounted in said enlarged portion, a friction locking plate having an aperture for receiving said intermediate rod, said bearing having a slot for receiving an end of said plate and a shoulder adjacent said slot for supporting said plate, said spring normally engaging said plate and said plate projecting beyond said bearing for engagement by the knee of the operator.

In testimony whereof I have hereunto subscribed my name at Chicago Cook County Illinois.

JOHN R. EMMERT.
